CLAIM

The ornamental design for a hand grip apparatus as shown and described.

DESCRIPTION

FIG. 1 is a front perspective view of a hand grip apparatus showing my new design;

FIG. 2 is a front side view thereof;

FIG. 3 is a back side view thereof;

FIG. 4 is a left side view thereof;

FIG. 5 is a right side view thereof;

FIG. 6 is a bottom view thereof;

FIG. 7 is a top view thereof; and,

FIG. 8 is front side view of a hand grip apparatus in an environmental use configuration with a person's hand and a baseball bat handle.

The broken lines in FIG. 8 that depict the environment of a person's hand and a baseball bat handle form no part of the claimed design.

1 Claim, 6 Drawing Sheets(56)
